ATTORNEY.

UNITED STATES PATENT OFFICE.

ULRICK SORENSEN, OF BERWYN, NEBRASKA.

GOVERNOR FOR TRACTORS.

1,407,957.

Specification of Letters Patent. Patented Feb. 28, 1922.

Application filed April 20, 1920. Serial No. 375,265.

To all whom it may concern:

Be it known that I, ULRICK SORENSEN, a citizen of the United States of America, residing at Berwyn, in the county of Custer 5 and State of Nebraska, have invented certain new and useful Improvements in Governors for Tractors, of which the following is a specification.

This invention relates to governors for tractors and more particularly to an automatic governor for the well known Fordson tractor and it has for its object to provide a governor adapted to be easily and quickly attached to the tractor aforesaid 15 utilizing certain of the existing parts of the tractor to support the same and utilizing the fan belt drive as a driving means for the governor.

Further objects and advantages of the invention will be set forth in the detailed description which now follows.

In the accompanying drawing Fig. 1 is a plan view of a governor constructed in accordance with the invention; and Fig. 2 25 is a perspective view showing a connection between the usual oscillatory throttle controlling rod of a Fordson tractor and a crank arm carried by the throttle valve stem of such tractor and showing in addition 30 means for connecting the governor to the crank arm on the throttle valve stem.

5 designates the cylinder head and 6 designates a part of a radiator shell of a well known Fordson tractor. A bearing 35 block 7 is secured by bolts or rivets 8 to the shell 6 while a plate 9 is secured by some of the cylinder head cap screws 10 in position to project laterally beyond the cylinder head and to lie in a horizontal position. This 40 plate carries a bearing 11 which together with the bearing 7 constitutes a support for a rotative shaft 12. The shaft 12 carries a drive pulley 13 over which a belt 14 passes. This belt is driven from the usual fan-pulley 45 15 and may be an extension of the fan belt itself.

A sleeve 16 is mounted to slide upon the shaft 12 and act against a thrust collar 17 carrying anti-friction elements such as balls 50 18. Weights 19 are pivoted at 20 to ears 21 of the pulley 13, and angularly extending tails 22 of said weights act against the end of the sleeve to thrust said sleeve toward the left when the weights move outwardly under centrifugal force. This action is against the tension of a spring 24,

one end of which bears against a collar 25. An L shaped lever 27 is pivoted at 28 to the plate 9. The arm 26 of lever 27 is forked and the arms of said fork lie between the collar 17 and the collar 25 and embrace the shaft 12 it being noted that said collar and washer are spaced apart a distance considerably greater than the thickness of arm 26 so that the fork may move 65 toward the left independently of these parts. The opposite end of the spring 24 bears against a collar 29 that may be adjusted lengthwise of the shaft 12 by means of set screw 30. Adjustment of this collar 70 regulates the rate of speed at which the engine will run; finer adjustments may be secured by manipulation of thumb nut 31 which is threaded upon a screw 32 to which one end of a spring 33 is connected. The 75 other end of this spring is connected at 34 to a long arm 35 of lever 27. The screw 32 passes through an ear 36 formed upon the plate 9. A link 37 is connected to the arm 35 at 38 and the opposite end of this 80 link is turned at right angles and passes through an extension plate 39 which is in turn secured by a screw 40 to the usual crank 41 on the valve stem 42 of the carbureter 43, it being understood that a turning motion of this stem 42 in one direction or the other serves to open or close the 85 throttle valve of the carbureter. A bearing bracket 44 is secured by one of the cap screws 10 of the cylinder head in position 90 to project laterally beyond the cylinder head and provide a bearing for one end of a rod 45. This rod carries a crank extension or yoke 46, an arm 47 of which projects through the crank extension 41 of the carbureter. This construction provides manually controllable means for actuating the 95 throttle valve, through which the engine may be idle when no work is being done and may be caused to run at any desired rate 100 of speed independently of the action of the governor, the capability of movement of the arm 26, independently of collar 17, permitting the manual actuation of crank 41 to rotate stem 42.

By reason of the great length of the arm 35 in comparison with the length of the arm 26 the governor is rendered extremely sensitive. The parts are so correlated and arranged that the device is in the nature of 105 an attachment adapted to be easily and quickly applied to a Fordson tractor with-

out any change in the present construction thereof. The governor is automatic and self contained, is of a simple, practical and durable design and is extremely sensitive to 5 all variations in the load carried by the tractor whether the engine is doing tractor or belt work.

Having described my invention, what I claim is:

- 10 The combination with a carbureter having a rotative throttle valve and a crank on the stem of said valve, of a manually operable rotative rod and a crank thereon engaging the first named crank, an extension upon 15 the crank of the throttle valve stem, a link connected to said extension, an L shaped lever comprising a long arm and a short arm, said lever being pivoted at its heel

and the extremity of the long arm having connection with said link, a centrifugal governor, an element actuated thereby with which the short arm of the L shaped lever engages and by which said arm is moved, said arm being capable of movement in one direction independently of the element and 25 a spring connected to said L shaped lever, the movement of said lever when manually operated being against the tension of said spring.

In testimony whereof I affix my signature 30 in the presence of two witnesses.

ULRICK SORENSEN.

Witnesses:

ARTHUR P. SCHNELL,
FRANK KELLY.
